James D. Jordan, Washington, D.C., assignor to the United States of America as represented by the Secretary of the Navy

Application September 20, 1943, Serial No. 503,146

6 Claims. (Cl. 200—80)

This invention relates to a switch for use in electrically fuzed rotating projectiles, and more particularly to a novel switch which operates to break a circuit for arming a projectile fuze.

In electrically operated projectile fuzes, an electrically fired squib is generally used to detonate a booster charge which, in turn, explodes the main charge of the projectile. In order to prevent premature firing of the squib by accidental actuation of the fuze, a short circuit around the squib is provided so that current which would otherwise operate the squib is by-passed around the squib, and the fuze remains unarmed as long as the short circuit is unbroken. Upon firing the projectile from a gun, an unshorting switch in the circuit is actuated to rupture the shorting circuit and arm the squib.

One object of the invention is to provide a novel unshorting switch for the above-described use, which is operable only upon firing of the projectile from a gun, or the like, and which will not be operated by dropping, jolting, or tumbling of the projectile.

A further object of the invention is to provide a device of the character described in which the centrifugal force caused by rotation of the projectile in its flight is utilized to break the shorting circuit.

A further object of the invention is to provide a device of the character described which will be simple and positive in operation and adapted to large scale manufacture.

These and other objects of the invention will be obvious from the following description and the accompanying drawing, in which

Fig. 1 is a longitudinal sectional view of one form of the new unshorting switch, with the parts in their unarmed positions;

Fig. 2 is a view similar to Fig. 1, but with the parts in their armed positions;

Fig. 3 is a cross sectional view taken on line 3—3 of Fig. 1;

Fig. 4 is an exploded view of the switch omitting the tubular casing and the end plugs,

Fig. 5 is a detailed longitudinal sectional view of a portion of another embodiment of the invention; and

Fig. 6 is a diagrammatic of the forward portion of a projectile, embodying the invention.

Referring first to Fig. 6 of the drawing, there is shown a projectile 7 having mounted therein an electronic control means 8 (which, for example, can comprise a radio proximity fuze including a thyratron), a squib and detonator unit 9 for firing the projectile 7 when the proper signal is received from the electronic control means 8, and the tubular casing 10 which includes the switch of the present invention.

In the embodiment of the invention shown in Figs. 1 through 4, the tubular casing 10 of insulating material is provided at its ends with plugs 11 and 12 through which electrical connectors 13 and 14, respectively, extend. In the interior of the casing are cylindrical inertia elements 15 and 16 of electrically conducting material, the inner ends of the inertia elements being separated by

a washer 17 of nonconducting material. The inertia elements 15 and 16 have axial passages 15a and 16a which receive and secure the ends of a frangible, electrically conducting element 18 extending through the center of washer 17 and providing an electrical connection between the inertia elements. The two spaced and insulated inertia elements 15 and 16 are thus initially and normally united by a separable joint, including the connecting pin or electrical conductor 18, and the safety switch thus formed is opened when the separable joint is disrupted or separated under centrifugal force created by a spinning projectile. The inner ends of connectors 13 and 14 extend into the outer ends of the axial passages 15a and 16a, respectively, the portion of each connector lying between the adjacent end plug and the adjacent inertia element being formed as a helix or spring, as shown at 13a and 14a, for a purpose to be explained presently.

In the operation of this embodiment of the invention, 20 the device with the parts in their unarmed positions, as shown in Fig. 1, is mounted in rotating projectile 7 transversely of the axis of rotation of the projectile, with the mid-point of the casing lying substantially at the axis of rotation of the projectile.

25 Connectors 13 and 14 are connected across a squib (not shown) so that the circuit comprising connector 14, inertia element 16, frangible element 18, inertia element 15 and connector 13 forms a short circuit around the squib. As long as this short circuit is unbroken, it will 30 prevent firing of the squib in case of accidental electrical operation of the fuze. The helical portions of connectors 13 and 14 act as compression springs and tend to hold the inner ends of inertia elements 15 and 16 against washer 17, as shown in Fig. 1. The purpose of these springs is to prevent accidental separation of the inertia elements, with resulting rupture of frangible element 18, by dropping or jolting of the device. Should the projectile 7 be dropped on its side, that is, in a direction longitudinally of the casing 10, the inertia elements 15 and 16 will move together in that direction, compressing the spring 13a or 14a at one end of the casing and extending the other spring. If the projectile 7 is dropped in a direction transversely to the casing 10, there will be no force tending to separate the inertia 40 elements 15 and 16. The strength of the springs and of frangible element 18 determine the magnitude of the speed of rotation necessary to operate the device, and these strengths are adjusted so as to prevent rupture of element 18 by rotations slower than that which takes place when the projectile is fired from a gun. Thus it is apparent that the device is safe against accidental 45 actuation of the unshorting switch.

When a projectile 7 containing the device is fired from a gun, the high speed of rotation of the projectile 7 in 50 its flight sets up large centrifugal forces which act on the inertia elements 15 and 16, resulting in outward movement of these elements away from each other and fracture of the frangible element 18, as shown in Fig. 2. Upon fracturing of the frangible element, the shorting 55 circuit is broken and the squib is armed.

The modification of the invention shown in Fig. 5 is the same as the embodiment shown in Figs. 1 through 4 except that the frangible connection 18 between the inertia elements is replaced by an electrically conducting projectile 19 screwed into inertia element 20 with its projecting end extending into a recess 21 in inertia element 22, the insulating washer 17a separating the inertia elements as in the device shown in Figs. 1 through 4.

60 The operation of the device shown in Fig. 5 is similar to the operation of the device shown in Figs. 1 through 4, except that separation of inertia elements 20 and 22 by centrifugal force on firing of the projectile

moves projection 19 out of contact with inertia element 22 to rupture the shorting circuit. It will be understood that the inertia elements 20 and 22 are normally urged inwardly by the springs 13a and 14a (Fig. 1).

If desired, separate springs may be provided at the outer ends of the inertia elements, instead of forming the conductors 13 and 14 in a helical shape. If separate springs are used, it is necessary to provide enough slack wire between the outer end of each inertia element and the adjacent plug to permit movement of the inertia elements toward the opposite end of the casing without danger of the connector breaking.

An important feature of the invention is that the two inertia elements will always tend to move together as a unit in the casing when they are moved by any force other than the centrifugal force caused by rotation of the projectile. As long as the inertia elements move as a unit, there is no danger of breaking the electrical connection between them. The tendency of the inertia elements to move as one element, except when acted upon by centrifugal force, is increased by the springs 13a, 14a which urge the inertia elements together.

It is to be understood that the switch is susceptible of various modifications within the scope of the invention. For example, the switch may be arranged so that the inertia elements act under centrifugal force to close a circuit rather than break a short circuit.

I claim:

1. In a centrifugal safety device for use in a rotating projectile, a tubular casing of nonconducting material mounted transversely of the projectile, an insulating plug at each end of the casing, two inertia elements mounted in said casing for movement longitudinally of the casing, said inertia elements being of conducting material, an insulating washer separating said inertia elements, a frangible, conducting element extending through said washer and having its ends connected to said inertia elements, and a connector attached to the outer end of each of said inertia elements and extending through the adjacent plug, the portion of each connector lying between the adjacent plug and the adjacent inertia element forming a spring to resist outward movement of the inertia elements, whereby the inertia elements and the frangible connector are movable as a unit in either direction against one of the springs, and said frangible element is ruptured by outward movement of the inertia elements under centrifugal force.

2. In a centrifugal safety device for use in a rotating projectile, a tubular casing of nonconducting material mounted transversely of the projectile, an insulating plug at each end of said casing, two inertia elements mounted in said casing for movement longitudinally of the casing, said inertia elements being of conducting material, an insulating washer separating said inertia elements, conducting means extending through said washer and forming an electrical connection between said inertia elements, a connector extending from the outer end of each of said inertia elements through the adjacent plug, the portion of the connector lying between the plug and the adjacent inertia element forming a spring to resist outward movement of the inertia elements, whereby the inertia elements and said conducting means are movable as a unit in either direction against one of the springs, and said electrical connection between the inertia elements is broken by outward movement of the inertia elements under centrifugal force. 65

3. In a centrifugal safety device for use in a rotating projectile, a tubular casing of nonconducting material mounted transversely of the projectile, an insulating plug at each end of said casing, two inertia elements mounted in said casing for movement longitudinally of said casing, said inertia elements being of conducting material, the inner end of one of said inertia elements having a recess therein, an insulating washer separating said inertia elements, a conducting element projecting from the other inertia element and extending through the washer into said recess to connect said inertia elements electrically, a connector extending from the outer end of each of said inertia elements through the adjacent plug, the portion of the connector lying between the plug and the adjacent inertia element forming a spring to resist outward movement of the inertia elements, whereby the inertia elements and said conducting element are movable as a unit in either direction against one of the springs, and said conducting element is withdrawn from the recess by outward movement of the inertia elements under centrifugal force.

4. In a centrifugal safety device for use in a rotating projectile, a tubular casing adapted to be mounted transversely of the projectile, a pair of inertia elements slideable longitudinally in the casing, said elements being of conducting material insulated from the casing and adapted for electrical connection outside the casing, biasing means for urging said elements together, and means normally connecting said elements electrically in the casing and operable to break the electrical connection in the casing between said elements upon outward movement of said elements away from each other under centrifugal force, said elements and connecting means being movable normally as a unit in the casing against the biasing means to maintain said electrical connection. 35

5. In a centrifugally operated safety device for use in a rotating projectile, a pair of electrically conducting inertia elements movable transversely of the axis of rotation of the projectile, a frangible, conducting element directly and integrally connecting said inertia elements, so that said inertia elements and said frangible element normally move as one unit, and biasing means for urging said inertia elements together, said inertia elements, said frangible element, and said biasing means constituting part of an electric circuit whereby upon the outward movement of said inertia elements under the influence of centrifugal forces, said frangible element is ruptured and simultaneously said inertia elements are released and said electric circuit is interrupted.

6. The combination in a centrifugally operated circuit-breaker, with an enclosing casing, of two spaced movable and insulating inertia elements forming part of an electric circuit, connecting means forming a separable joint uniting said inertia elements electrically as well as mechanically, said connecting means being frangible, and resilient means within the casing for absorbing bodily movement of the jointed structure. 55
